UNITED STATES PATENT OFFICE.

HENRY C. SALTIEL, OF RAWLINS, WYOMING.

JOURNAL-BOX.

1,380,256.

Specification of Letters Patent. Patented May 31, 1921.

Application filed March 1, 1920. Serial No. 362,341.

To all whom it may concern:

Be it known that I, HENRY C. SALTIEL, a citizen of the United States, residing at Rawlins, in the county of Carbon and State 5 of Wyoming, have invented new and useful Improvements in Journal-Boxes, of which the following is a specification.

This invention relates to bearing devices for journals and has for its object the provision of a novel bearing including a box structure having one side open for the insertion of the brass journal, the open side being subsequently closed by concaved inserts bolted in place and coöperating with 15 the associated parts for holding the journal properly in position.

An important object is the provision of a device of this character which will be simple and inexpensive in manufacture and assembly, highly efficient and durable in use, and 20 a general improvement in the art.

With the above and other objects and advantages in view, the invention consists in the details of construction to be hereinafter 25 more fully described and claimed and illustrated in the accompanying drawings in which—

Figure 1 is a view of my complete device, Fig. 2 is a side view of the oil box, 30 Fig. 3 is an end elevation thereof, and Fig. 4 is a perspective view of the insert.

Referring more particularly to the drawings, the numeral 10 designates a wheel carrying a stub 11 surrounded by a brass journal 12. Supporting the journal and consequently the stub and wheel, is an oil box 13 filled with suitable packing 14 and within which the journal is disposed, the stub projecting beyond the end of the journal. One 40 side of the box 13 is shown open, as at 15, to permit insertion or removal of the journal and the journal is normally held in position by an insert 16 which is formed preferably of steel and which is made as an 45 elongated body 17 having right angular end

portions provided with holes 18 for the reception of bolts 19 by means of which the inserts are secured to the box. The insert has a concaved face 20 for engagement with the journal whereby to conformingly engage 50 the same. I also make use of a suitable wedge 21 which is located above the member 12.

When the parts of my device are constructed and assembled as above described, 55 it will be apparent that there will be thus provided an extremely highly efficient and durable journal box which may be readily disassembled if required and in which the parts may be easily replaced if broken or 60 worn.

While I have shown and described the preferred embodiment of my invention, it is of course to be understood that I reserve the right to make such changes in the form, 65 construction, and arrangement of parts as will not depart from the spirit of the invention or the scope of the subjoined claim.

Having thus described my invention, I 70 claim:

In combination, an oil box having one side formed with an opening, means for closing the opening, a stub axle extending from the wheel and disposed within said box, the opening in said box being of a size 75 to permit passage of said stub axle, a journal bearing surrounding said stub axle, a wedge member disposed at the top of the box and engaging the top of said journal, and means for retaining the stub and journal within 80 the box comprising an insert located within the open end of the box and having one face concaved for conforming engagement with the journal, said insert having right angularly extending ends bearing against the 85 underside of the top and the top side of the bottom of the box and being bolted to the latter.

In testimony whereof I affix my signature.

HENRY C. SALTIEL.
